UNITED STATES PATENT OFFICE.

JOSEPH O. RICHARD, OF DETROIT, MICHIGAN, ASSIGNOR TO HAYES MANUFACTURING COMPANY, OF DETROIT, MICHIGAN, A CORPORATION OF MICHIGAN.

CURLING MACHINE.

Application filed March 20, 1922. Serial No. 545,014.

To all whom it may concern:

Be it known that I, JOSEPH O. RICHARD, citizen of the United States, residing at Detroit, in the county of Wayne and State of Michigan, have invented certain new and useful Improvements in Curling Machines, of which the following is a specification.

This invention relates to curling machines and especially to machines for curling the knuckle eye of a hood hinge for an automobile body. It has been customary to use machines which simultaneously operate on all the blanks to form the entire number of eyes. In the first action the blanks are turned over part way and in the next action the eyes are completed. This form of machine has not been entirely satisfactory. It requires an expensive set of dies as dies have to be provided for the numerous knuckles or eyes.

It is the object of the present invention to provide a curling machine in which the work travels past three sets of dies. These dies are automatically caused to engage the work and perform the two separate curling operations necessary to turn the metal into an eye. In order to save time the machine works in either direction, that is, on the forward stroke of the work table a piece of material can be carried by the dies and completed. On the return stroke, a blank is set on the table and is completed when the table reaches its initial position. These features will be best understood when a complete description of the machine has been given.

In the drawings:

Figure 1 is an end elevation of the machine taken from the left of Fig. 2.

Fig. 2 is a front elevation of the machine.

Fig. 3 is a section taken on the line 3—3 of Fig. 2.

Fig. 4 is a section taken on the line 4—4 of Fig. 3.

Fig. 5 is an enlarged sectional detail taken on the line 5—5 of Fig. 3.

Fig. 6 is a perspective of the driving dog.

Fig. 7 is a section through the crank or the driving wheel.

Fig. 8 is a section on the line 9—9 of Fig. 7.

Fig. 9 is a plan view of the work table.

Fig. 10 is a front elevation of a part of the machine showing the dies.

Fig. 11 is an end elevation showing the dies.

Fig. 12 is a plan view of a piece of work.

Fig. 13 is a section showing the first operation performed on the work.

Fig. 14 is another section showing the second operation performed on the work.

Referring to Fig. 1, *a* designates a large gear wheel driven by suitable connections (not shown) from the pulley wheel *b*. This gear wheel is connected by a crankshaft *c* with the driving wheel *d* (Fig. 2). *e* designates a brake band that encircles the driving wheel. Clamped to the driving wheel by the bolts *f* is a dove-tailed crank member *g* adapted to take the slide *h* (see Figs. 8 and 9). This slide *h* is provided with a special stud *i* on which is adapted to be screwed the bushing *j* and the nut *k*. This bushing *j* serves as a bearing for the end of the connecting rod *m*. The crank is arranged to take a long screw *n* which is threaded into the slide *h*. By loosening the bushing and the nut on the stud *i* the slide is freed so that it may be adjusted with accuracy by turning the screw *n*. By again tightening up the bushing and the nut the adjustment is fixed. This serves to regulate the throw of the crank so as to adjust the travel of the machine, as hereinafter to be explained, to knuckles of varying lengths. The brake *e* is simply a split band that encircles the driving wheel *d* and it is held against the brake drum surface by the spring *o*. This serves simply as a brake upon the driving wheel to prevent the same overrunning when the power is thrown off.

Referring to Fig. 1, it will be seen that the dove-tailed crank member *g* is connected with the sliding rack *p* by means of the connecting rod *q*. The length of the connecting rod may be altered by means of the turn-buckle *r* to accord it with any new length of throw introduced into the crank. The rack *p* slides vertically in the guide-way *s*. This is shown in detail in Fig. 3. The teeth of the rack engage the teeth of the composite gear *t*. This gear is made up of two halves and has its hubs running loosely on the ratchet wheel *u*, (see Fig. 3) which is keyed to the driving shaft *w*. Now referring to Fig. 5, it will be seen that the composite gear has a recess *x* in which is pivoted the driving dog *y*. The result of this construction is that

on the up stroke of the rack *p* the composite gear *t* through the rack and the dog drives the drive shaft. On the return stroke the driving gear *t* rides inactively over the ratchet wheel. This results in a step by step movement of the driving shaft *w*. The gear *t* is a composite gear so as to permit access to the ratchet wheel and dog inside.

Keyed on this driving shaft *w* are a pair of pinions *z* (Fig. 3) which may be shifted by the fork 1. It will also be seen (Fig. 4) that there is an adjoining stationary shaft 2 on which rotate and slide the two pinions 3. The two shifting forks 1 and 4 are connected to the shifting rods 5 and 6 respectively. The ends of these rods are provided with rolls 7 which engage in the cam race 8 of the dovetailed slide 9 of the bracket 10. The bracket 10 is bolted to the side of the bed 11 of the machine. A handle 12 is secured to the slide 9. By shifting this handle one way or the other from the position shown in Fig. 4, which is in neutral position, either one pinion or the other may be brought into engagement with the rack 13 (Fig. 1) (Fig. 3). These devices are simply a means for reversing the drive on the rack 13. The rack 13 is bolted to the work table 14 (Fig. 3) which slides on the tracks 15 on the bed of the machine.

This work table is shown in plan in Fig. 10 and has a pair of outwardly-extending arms 16 provided with dovetail ways 17, arranged to take the slides 18, thru which run the threaded rods 19. These slides support a gauge bar 20. By turning the rods 19 with a suitable crank 21 (Fig. 1) the gauge bar 20 may be moved toward or away from the back of the table to adjust the gauge bar to work with given dimensions. It may be clamped down by the nuts 100 on the end of the threaded stud 101.

Supported on the work table is a clamping mechanism comprising posts 22 set vertically on the table. These posts are connected at the top by the angle bar 28. The saddles 23 are provided at the ends of the platen 29. Wedge blocks 24 are secured to the ends of the piston rods 25 which run through the air cylinder 26 controlled by the slide valve 27. These wedge blocks engage against the inclined faces of the abutment block 102. The slide valve is thrown to one position or the other by the lever 30. The air is only used to force the platen 29 downward against the work. The springs 31 (Fig. 3) serve to lift the platen when the air is exhausted in the cylinder. Air is furnished to the air cylinder by a flexible hose 32 so that the cylinder may travel over the table. Referring to Figs. 14 and 15, it will be seen how the platen 29 clamps the work 33 to the edge of the table 14.

As already explained, the table moves step by step due to the intermittent motion provided by the ratchet gear and rack drive.

This movement is proportioned to the length of the knuckle eyes by means of adjusting the crank throw as already explained. In Figs. 14 and 15 the two operations effected on each knuckle eye blank are shown. The first operation is turning over the edge of the blank, as shown in Fig. 14. This is accomplished by a stationary die 34 fastened to the bed 35 of the press and a movable die 36 fastened to the die carrier 37 of the press. The next operation is the curling over of the knuckle eye as shown in Fig. 14. This is accomplished by the single finishing die 38 slideable horizontally by reason of the cam strip 39 bolted to the die-carrier 37 of the press. This cam strip engages the roll 40 and forces the die out against the turned-over end of the knuckle blank. Referring to Figs. 11 and 12, it will be seen that there are two upper vertical dies 36 bolted to the ram and two lower dies 34 bolted to the bed of the press. There is a single horizontal die 38 slideable in a suitable groove of the press bed 35 by means of the cam strip 39 engaging the roll 40. Referring to Fig. 11,—41 represents the two vertical uprights or guides for the press ram. The die carrier is designated 37 and is bolted to the ram 42 by means of the bracket 43 and bolts 44' and 45'. This ram 42 is connected with a cross head 44 by means of the adjusting screw 45. 46 designates the connecting rod between the crankshaft of the press and the cross head 44. The operation is as follows:

The work is placed on the table blanked out, as shown in Fig. 13, the screws 19 having previously been turned to bring the gauge bar 20 to the proper position. The block 46' is adjusted along the gauge bar 20 by means of the bolt 47, the slot 48 and the perforations 49 in the gauge bar. This serves to determine the position of the work sheet in one direction while the gauge bar determines the position of the work sheet in the other direction.

The lever 30 is now operated to let the air into the cylinder 26. This immediately moves the piston rods 25 to the left, throwing the wedge blocks under the inclined abutments 102 (Fig. 1), thereby forcing the saddles 23 and the platen downward. This, of course forces the entire platen, piston rods and air cylinders downward, clamping the work as shown in Figs. 14 and 15.

The power is now shifted on in any suitable way. This starts the gear *a* to rotating, forcing down the connecting rod *q* idly over the driving ratchet. However, the main crank of the press goes down and through the connecting rod 16 and other connections it forces the ram of the press down. The first action is for the nipping die 36 to turn over the edge of the knuckle blank, as shown in Fig. 14. The dies then separate and in the meantime the connecting rod *q* is pulled

up and through the rack *p* drives the ratchet and consequently through the driving pinions and rack drives the table forward to the left. The brake 51 (Fig. 1) serves as a drag upon the drive shaft so that it will not carry beyond due to momentum after the driving effort has been disconnected. This travel of the table is properly adjusted through the adjustable crank throw already explained so that the travel of the table is just the length of the knuckle blank.

This movement of the work table has now brought the first knuckle blank into the path of the horizontally moving finishing die 38 which comes forward, as shown in Fig. 15, and finishes the knuckle or the eye. The next following knuckle blank is under the right hand set of vertical-moving or nipping dies and the first operation is, therefore, taken on the succeeding knuckle blank. The dies now separate and the table moves again to the left. However, the finished knuckle clears the left hand set of vertical-moving or nipping dies (the latter shown in Fig. 11). The knuckle blank has been turned in far enough so that with the aid of the notch 53 in the lower nipping die the knuckle does not come within the path of the two dies. This operation continues until all the knuckle blanks are finished. Then the power shifting lever 104 (Fig. 2) slips off the end of the angle bar 28 and stops the machine by throwing out a clutch, not shown.

The work is taken out by releasing the air pressure in the cylinder 26, a new blank is put in place, the reversing gears are shifted with the handle 12, and the work table is started back. The action is precisely the same except on the backward movement the left hand set of nipping dies, shown in Fig. 11, become active dies while the right hand set of nipping dies become inactive and idlers.

Although in the specification and claims I have referred specifically to knuckle eyes and knuckle blanks, these references must not be taken as limitations; but merely words of description. The structure claimed can be used wherever it is required to curl the edges of sheet metal. Hence the claims must be understood in this broad sense.

Also, in the claims the dies have been referred to as vertically-moving and horizontally moving dies. Obviously these are simply terms of relativity and hence not words of limitation but words of description.

What I claim is:

1. In a curling machine, the combination of two pairs of vertically-operating dies for performing the initial curling operation on a knuckle blank, a die for finishing the curling operation on a preceding knuckle blank, the vertically-operating dies being arranged so that with the movement of the work through the dies one set of the vertical dies become idlers when the work is moved

through in one direction and active when the work is moved through in the opposite direction, and vice versa.

2. In a curling machine, the combination of two pairs of vertically-operating dies for performing an initial curling operation on a knuckle blank, a horizontally-movable finishing die for completing the curling operation, said vertically-operating dies being arranged so that when the work goes through the dies in one direction the finished knuckle eye clears one set of vertically-moving dies so as to make idlers of the same and when the work goes through in the opposite direction the finished eye or knuckle clears the other set of vertically-operated dies to make them idlers.

3. In a curling machine, the combination of two pairs of vertically-operating dies for performing an initial curling operation on a knuckle blank, a horizontally-moving finishing die located between the two pairs of vertical dies, the said dies being arranged so that the first pair of vertically-operated dies serves to operate upon the knuckle or eye while the work passes the second set of vertically-operating dies which are idlers but which become active dies when the work is passed through in the opposite direction.

4. A curling machine, having in combination, a pair of vertically-operating dies for performing an initial curling operation on knuckle blanks, a horizontally-moving finishing die for performing the finishing operation on the preceding knuckle blank, and a press ram carrying the upper vertically-operating die and simultaneously actuating the finishing die.

5. A curling machine, having in combination, a pair of vertically-operating dies for performing the initial curling operation on the knuckle blanks, a horizontally-movable finishing die for performing the finishing operation on the preceding knuckle blank, a ram carrying the upper vertically-operated die, and a cam strip carried by the ram engaging the horizontally-moving finishing die but simultaneously actuating the dies.

6. A curling machine, having in combination, a traveling table for supporting a sheet of metal provided with a plurality of knuckle blanks, vertically-operating dies for initially forming the knuckle eye and a horizontally-operating die for finishing the curling operation, a press provided with a vertically-moving ram for carrying the vertically-operating dies and simultaneously operating the horizontally-moving die, and connections between the press and the work table for intermittently moving the work table while the dies are separated.

7. A curling machine, having in combination, a reciprocating work table, a plurality of dies for operating on a portion of the blank to curl the same into a knuckle eye,

means for intermittently moving the table to bring successive portions of the work into engagement with the dies, and means for reversing the movement of the table, the said dies being arranged to operate on successive parts of the work as it is fed in either direction by movement of the table.

8. A curling machine, having in combination, a traveling work table arranged to take a sheet of metal, posts supported on the table, a platen slidable on said posts, means for forcing the platen down against the sheet metal adjacent one edge to clamp the same in place, and dies arranged to operate on the projecting edge portion of the sheet metal to turn the same in.

9. A curling machine, having in combination, a work table arranged to slide and designed to take a sheet of metal, posts projecting upwardly from said table, a platen guided vertically in sliding movement by said posts, and pneumatic means for forcing the platen and holding the same down against the sheet metal and adjacent one edge, and dies through which the edge portion of the sheet metal may be fed to turn the same over.

10. A curling machine, having in combination, a moving table arranged to take a sheet of metal, posts projecting upwardly from said table and provided with abutments, a platen guided in vertical reciprocation on said posts, a pair of wedge blocks

arranged to engage the abutments, supported by said posts for forcing said platen down against the sheet metal near one edge to clamp the same in place and hold it in such position, and means for moving the said wedge blocks to force the platen down against the sheet metal, and means for turning over the edge of the sheet metal.

11. A curling machine having in combination a travelling work table for supporting a sheet of metal having one edge blanked out to form a plurality of knuckle blanks, means for clamping the said sheet of metal, means for intermittently moving the work table, and dies for simultaneously engaging successive knuckle blanks of the sheet to initially curl one knuckle blank and finish the curling of the next knuckle blank.

12. A curling machine having in combination a travelling work table for supporting a sheet of metal having one edge blanked out forming a plurality of knuckle blanks, means for intermittently feeding the table forward and backward when the table has been reversed, and dies for simultaneously operating on successive knuckle blanks to curl one initially and finish the curling of the next one, the said dies so operable whether the travel of the table is forward or backward.

In testimony whereof I affix my signature.

JOSEPH O. RICHARD.
